UNITED STATES PATENT OFFICE.

GUSTAVE GABET, OF ROCHEFORT-SUR-MER, FRANCE.

APPARATUS FOR OPERATING MECHANISM FROM A DISTANCE.

No. 907,488.

Specification of Letters Patent. Patented Dec. 22, 1908.

Application filed September 29, 1905. Serial No. 280,632.

To all whom it may concern:

Be it known that I, GUSTAVE GABET, a citizen of the Republic of France, residing at 9 Rue Baudin, in Rochefort-Sur-Mer, Charente Inférieure, in the Republic of France, professor, have invented certain new and useful Improvements in Apparatus for Operating Mechanism from a Distance, of which the following is a specification.

10 The present invention has for its object apparatus whereby it is possible to control or operate from a distance, by luminous or electrical waves, an engine, a rudder, a dirigible torpedo, a signal, or any other mechanism.

15 The apparatus consists broadly of a pallet wheel driven by a clockwork movement, provided with a ratchet wheel and advancing by one pallet under each impulsion of the 20 succession of waves. Certain of the pallets carry a sinuous path of insulating material in which circulates a drop of mercury, which, under the influence of gravity, closes the circuit of the selected control, when the wheel 25 is locked.

The device is represented by way of example in the accompanying drawing, in which:

30 Figure 1 is a side elevation of the pallet wheel. Fig. 2 is a section on the line A—B of Fig. 1. Fig. 3 shows in elevation the pallet wheel and in section the crown producing the eclipses to be hereinafter described. Fig. 4 is an upper view of one of the brushes 35 rubbing upon the crown. Fig. 5 is a section upon a larger scale on the line C—D of Fig. 3. Fig. 6 is a view of the optical device producing the eclipses. Fig. 7 is a diagrammatic view of the relay for coöperation with 40 the electro-magnet. Fig. 8 is an enlarged detail of the pawl and ratchet. Fig. 9 is a diagrammatic view of one of the controlling devices.

45 The pallets 1, 2, 3, 4, 5 and 6 which effect the various controls, are mounted upon the spindle 7 which is driven by a clockwork movement. The spindle 7 carries the wheel 8 between the teeth of which engages the pawl 9 which is actuated by the electro magnet 10. It is upon this electro magnet that 50 the lines or successions of waves act by the intermediary of an ordinary relay.

55 At the transmission station only two things can be done: despatch a succession of waves (by depressing the sender) or not despatch them.

At the receiving station, in the first case the pawl 9 is attracted by the electro magnet 10; in the second case, the pawl remains in place, held there by its opposing spring. 60 It is exactly the case of the lever of the Morse apparatus writing the telegram on a strip of paper by means of intervals in the emissions of the trains of waves.

65 The object in view is as follows:—Given this reciprocating movement of the pawl 9, utilize it for producing varied effects (provided for in advance) of the controls and this by closing different circuits, specially assigned to a particular control. All this 70 takes place without any necessity for the intervention of the operator at the receiving station, which may therefore be situated at an isolated spot, abandoned or inaccessible 75 at the moment of the operation.

For the sake of clearness assume a motor placed at a certain spot and an operator posted at another spot, situated at a certain distance from the former. Without coming near the motor it is possible for the operator, 80 from a distance, to effect the three following controls; starting the motor forward, backward and stopping it. In this case the pallet wheel will comprise six pallets, for example: three corresponding to the three controls indicated above and the others being repose pallets, that is to say pallets not carrying either glass tube or bead of mercury and which may thus be left in "position of control" in the intervals between the "controls" properly 85 so called. In the first place therefore we have to show the manner in which the electro magnet 10 is energized. The waves may come from two different sources: from the emission instrument manipulated by the 90 operator or from some foreign apparatus. The "device for control from a distance" is in fact independent of the system of wireless telegraphy employed, because it is only the utilization of a kinematic fact: the re- 100

105 reciprocating movement of the pawl 9. The electro magnet 10 therefore attracts the pawl 9, the ratchet wheel 8 escapes by one tooth and the pallet wheel, acted upon by the clock-work movement, progresses by half the interval between two pallets. The ratchet wheel 8 carries a number of teeth double the 110 number of pallets. When the train or succession of waves ceases, the electro magnet 10 ceases to attract the pawl 9 and this latter, returned by its opposing spring, permits of the escape of a fresh tooth of the wheel 8.

At this moment a pallet has reached its contact position. The pallet wheel therefore does not rotate throughout the entire duration of the emission of the train of waves. If 5 this latter is prolonged it only stops the wheel in a position intermediate between the foregoing position and the "control position".

Foreign instruments might act upon the electro magnet 10. It is in order to obviate 10 this inconvenience that the optical indicator described is utilized.

The operator should know the position of the wheel at each moment in order that he may be able to stop it at the moment at 15 which the pallet which corresponds to the control that he desires to carry out has come beneath the horizontal plane, because it is at this moment that gravity acts upon the bead of mercury tending to cause it to move from 20 the center towards the periphery. The drop of mercury closes the circuit 17, 16, 15, 13, 14, 19, 20, 22 and 23 which comprises a battery and an electric magnet not shown. This magnet is a relay which is energized and 25 attracts a pallet closing another circuit which produces the desired control.

The optical indicator described may consist of a single lamp visible to the operator. This lamp is inserted on a special circuit 30 comprising a source of electricity, the ring 24 and the springs 32 and 33.

Assuming, for the sake of clearness, that the insulating strips 29 and 30 are arranged in such a manner that the extinction of the 35 lamp takes place immediately before the pallet corresponding to the stoppage of the motor has passed beyond the horizontal plane in order to reach the contact position. When the operator has seen the two extinctions of the lamp, he will know that the 40 pallet which has thus reached the control position is in fact that which corresponds to the stoppage of the motor, that the first pallet which will subsequently pass corresponds to 45 forward travel, the second to backward travel, that the succeeding pallets are pallets of repose, and so on. For the first pallet he will see two extinctions of the lamp and one for each of the others. By counting 50 the eclipses the operator will know at each moment the position of the wheel at the receiving station, from which he is separated by insurmountable obstacles at the moment of the operation. It is for this reason that 55 the question of actuating the apparatus by hand does not arise, as the apparatus is constructed for control from a distance. If during the interval between the controls the pallet wheel should be caused to occupy a 60 non-operative position (pallet of repose in position of control) it is in order to obviate the necessity for the operator constantly causing the pallet wheel to rotate, in order that the drops of mercury may not have 65 time to close any circuit such as 17 to 23.

The operator might, it is true, at once place the selected pallet in the control position without having to look for the double extinction of the lamp, but only if he is quite certain that no double extinction of the lamp 70 has taken place which he has failed to count. The double extinction of the lamp therefore relieves the memory and the attention of the operator.

The drop of mercury does not close the circuit of the lamp but the circuit 17 to 23 in which the relay producing the desired control is interposed, and the clip 32, 33 is placed in a position such that the eclipse corresponding to a given control may take place at the precise 80 moment at which the pallet attains its "position of control" while the circuit 17 to 23 will only be closed four seconds later for example (the time occupied by the drop of mercury in finishing its descent and come 85 into contact with the electrodes 13—14).

If a foreign wave emission apparatus has caused the wheel to rotate and then permitted it to stop, the operator will be aware of this because he has counted the extinctions 90 of the lamp. Before the drop 12 has closed the circuit the operator has time to despatch waves which once again bring the wheel into a position of repose and thereby prevent any control from taking place.

In each pallet corresponding to a control is arranged a sinuous track or path constituted by a glass tube 11 of from 3 to 4 millimeters internal diameter. A drop of mercury 12 is introduced into this tube and thereupon a 100 vacuum is formed therein. At the extremity of the tube are mounted two platinum points 13 and 14 fused into the glass. These points are separated by an interval of say 1.5 mm. and are adapted to be electrically 105 connected by the drop of mercury. The point 13 communicates with a wire 15 connected to a ring 16 let into the hub of the pallet wheel, which hub is of insulating material. The electric current reaches the ring 110 16 by the intermediary of the brush 17 which enters a groove formed in the hub 18 and at the bottom of which the ring 16 is situated. There are as many rings, grooves and brushes as there are pallets carrying controlling 115 means. The point 14 is electrically connected by the wire 19 to a ring segment 20 (Fig. 5) partially embedded in a washer of insulating material and separated from the other similar rings by insulating washers 21. The 120 ring 20 presents a projection 22 which is free. When this projection is opposite the brush 23, the electric current is able to traverse the circuit 17, 16, 15, 13, 14, 19, 20, 22 and 23, assuming that the drop of mercury 12 is 125 touching the points 13 and 14. This is what occurs when the apparatus is locked in the desired position. The operator who produces the emission of the lines or successions of waves thus produces an action which has 130

been determined in advance, such as the stopping or starting of a motor, the explosion of a torpedo and so forth.

It is in order to prevent the circuit of each control from being closed in all the positions of the corresponding pallet, while this latter is below the horizontal plane, that the disposition represented in Fig. 5 has been adopted. Each control of course carries a ring and a brush such as 20 and 23, but the length of each ring is variable and is a function of the angular displacement necessary for causing the closing of the circuit in the sole contact position.

15 In order that the operator may be able to act at the desired moment, it is essential that he should know exactly what the position of the pallet wheel is at each moment. This result may be obtained by means of two appliances advancing synchronously under the influence of the lines or successions of waves, but this method does not afford any security. The transmitting and receiving stations are usually separated by a considerable distance 25 and it might be that one of the stations was influenced by certain successions of waves which would not affect the other.

The arrangement described below obviates this defect and renders it possible for the operator to keep himself acquainted with the exact position of the pallets of the wheel at all times. This wheel is provided, screwed to the edge of the pallets, with a ring of copper 24 provided at intervals with insulating strips 25, 26, 27, 28, 29, 30 and 31. These strips correspond to the various pallets carrying the controls.

In order to establish a datum, one of the controls (5 in the example chosen), corresponds to two insulating strips 29 and 30 separated by an interval of some millimeters. A clip, formed by two springs 32 and 33 forming brushes and mounted upon an ebonite cube 34, is supported by the rod 35 opposite the ring 24, in such a manner that in the rotation of this latter the insulating strips come in succession between the brushes 32 and 33.

Fig. 6 represents the optical device producing the eclipses, and comprising the crown 24, the springs 32 and 33, the wire 45, the lamp 46, (placed on the top of a mast for example, and visible only to the operator, owing to a screen which sends all the luminous rays towards him), the wire 47, and the source of electricity 48.

The relay acting upon the electro-magnet 10 is represented in Fig. 7.

The electric waves reach the wire 37 carrying the coherer 38 through an antenna. The electro-magnet 39 when it is energized closes the circuit of the electro-magnet 10 which attracts the pawl 9.

The counter spring 36 maintains the pawl 9, in the position of repose during the inter-

vals between the arrival of the trains of waves.

Fig. 9 shows a diagram of one of the controlling means. When the proper pallet is in the "controlled position" and the wheel is stopped, the projection 22 (Fig. 5) is opposite the brush 23. The drop of mercury is in contact with the points 13 and 14 and the circuit is closed over 17, 16, 15, 13, 14, 19, 20, 22, 23, the electro-magnet 40 and the source 70 of electricity 41. The electro-magnet 40 then closes the circuit 42, 43, comprising a source of electricity 44 and terminating at the parts charged with effecting the desired operation. All the brushes such as 17 communicate with the source of electricity 41 on the one hand, and on the other hand with a circuit similar to the foregoing and comprising an electro-magnet such as 40 which closes a circuit such as 42, 43, and which is likewise 85 connected with the source of electricity 44. In short, it is in the circuits 42, 43, that the appliances producing the effects, that the operator at the transmitting station desires to obtain, are situated.

90 For the sake of clearness, the various circuits described above are represented separate from each other.

The "controlled position" mentioned above is the only one. It is that in which 95 the pallet 1 (Fig. 1) is situated that is to say the first position below the horizontal plane passing through the axis of the wheel, in which all the pallets stop in succession.

Owing to the double extinction of the lamp 100 produced by the strips 29 and 30, the operator need only count the successive extinctions of the lamp in order to know the exact position of the pallet wheel at any moment and the manipulation required for producing 105 the desired control.

This apparatus likewise presents another advantage of great importance. The velocity of light being treated as infinite, the operator by reason of the position actually 110 occupied by the clip, perceives the extinction of the lamp corresponding to the control that he desires to produce at the precise moment at which the pallet reaches its operating position. Now, the drop of mercury, tending to move away from the center and towards the periphery, occupies an appreciable time (which is a function of the inclination and of the sinuosities of the insulating tube) before it makes contact with the points 13 and 14. 115 If this period is four seconds, for example, the selected control will not be produced until four seconds after the operator has observed the extinction of the lamp. The operator is accordingly notified, some few seconds before its execution, that the operation 120 is about to take place, and he still has time, in case the operation in question should not be that which was selected, to prevent this operation before it produces its effect. It 125 130

would only be necessary for him to depress his Morse key and thereby emit a succession of waves causing the wheel to advance by one pallet before the mercury has been able to close the circuit. In practice, therefore, this apparatus enables the operator to correct any errors in operation before they have produced any disturbance in the apparatus actuated. Its importance becomes especially great when it is applied to a maritime device (to a dirigible torpedo for example) as it permits of nullifying before they can take effect, any controls attempted by the enemy which might, by chance, have escaped the tuning or syntonzation devices employed.

What I claim and desire to secure by Letters Patent of the United States is:—

1. Apparatus for effecting control from a distance by luminous or electrical waves, consisting of a pallet wheel driven by a clock-work movement, provided with a ratchet wheel and advancing by one pallet at each impulsion of the line of waves, the pallets producing the controls containing each a sinuous tube of insulating material, free from air and containing a drop of mercury which under the influence of gravity makes contact with two conducting points fused into the tube and interposed in an electric circuit the closing of which produces the control, the delay in making the contact which arises from the time occupied by the mercury in traversing the tube, permitting the operator to rectify operative errors or to nullify outside or unauthorized operations before they have had time to produce their effect substantially as set forth.
2. In an apparatus for effecting control from a distance by luminous or electrical waves, a pallet wheel, clock-work for driving the same, a ratchet wheel, means for advancing the same by one pallet at each impulsion of the line of waves, each pallet embodying a sinuous tube of insulating material free from air and containing a drop of mercury, two

conducting points in one portion of said tube, ring segments of different lengths embedded in an insulator with projections extending through the latter, and brushes for coöperation therewith to close the circuit only in such position of the pallet wheel that the brushes and projections come into contact with each other.

3. In an apparatus for effecting control from a distance by luminous or electrical waves, means for lighting and extinguishing the lamp, a pallet wheel, clock-work for driving the same, a ratchet wheel, means for advancing the same by one pallet at each impulsion of the line of waves, each pallet embodying a sinuous tube of insulating material free from air and containing a drop of mercury, two conducting points in one portion of said tube, a ring of copper connected with said wheel and insulating strips carried by said ring in front of each pallet and which during the rotation of the wheel produce extinctions whereby counting the extinctions which follow two extinctions succeeding each other rapidly by reason of said two insulating strips being side by side, the position of the pallet wheel may be known at all times.

4. In an apparatus for effecting control from a distance by luminous or electrical waves, a wheel with pallets each embodying a sinuous tube with conducting points, said tube being free from air and containing a drop of mercury, ring segments electrically connected with one of said points and presenting projections, and brushes for coöperation with said projections, said rings being of variable length as and for the purpose specified.

In testimony whereof I have hereunto set my hand in presence of two subscribing witnesses this eighth day of September 1905.

GUSTAVE GABET.
